UNITED STATES PATENT OFFICE.

HENRY BERRY, OF SHELTON, ASSIGNOR TO THE DERBY SILVER COMPANY,
OF DERBY, CONNECTICUT.

DESIGN FOR A BOWL, &c.

SPECIFICATION forming part of Design No. 24,036, dated February 12, 1895.

Application filed December 18, 1894. Serial No. 532,266. Term of patent 7 years.

To all whom it may concern:

Be it known that I, HENRY BERRY, a citizen of the United States, residing at Shelton, in the township of Huntington, county of Fairfield, and State of Connecticut, have invented and produced a new and original Design for a Bowl for Tea-Sets and Similar Articles, of which the following is a specification, reference being had to the accompanying drawings, forming a part hereof, in which—

Figure 1 is a side elevation of a bowl bearing and incorporating my design; and Fig. 2 is a top view of same.

The leading features of the design consist in the novel form and configuration of the bowl, the latter being polygonal in cross-section and swelling outward from its upper edge and thence curving downward and inward to the base, the upper convex portion of the bowl being encompassed by a broad band bearing ornamental scroll work, substantially as shown in the accompanying drawings.

In the drawings A designates the body of the said bowl, which, as illustrated more clearly in Fig. 2, is hexagonal in outline and

the sides of which converge downward and inward to the circular base B, which at its upper edge has the annular bead C whence the sides of said base extend downward and outward to an ornamental beaded edging D, as shown in Fig. 1. The upper portions of the sides of the body A turn upward and inward on graceful convex lines and are encompassed by a broad band E of ornamental scroll work 35 supplemented at its base by the continuous line of beading F. It will be noticed that the hexagonal feature of the bowl is continued from the upper edges of the latter through the convex ornamental band E and downward 40 to the annular bead C of the base.

What I claim is—

The design for a bowl for tea-sets and similar articles, substantially as shown and described.

Signed at Shelton, Connecticut, this 15th day of December, 1894.

HENRY BERRY.
